UNITED STATES PATENT OFFICE.

ULYSSE PERRIER, OF NEW YORK, N. Y., ASSIGNOR, BY DIRECT AND MESNE ASSIGNMENTS, TO THE GENERAL AUTOMATIC DELIVERY COMPANY, OF SAME PLACE.

COIN-CONTROLLED APPARATUS.

SPECIFICATION forming part of Letters Patent No. 645,234, dated March 13, 1900.

Application filed September 29, 1899. Serial No. 732,012. (No model.)

To all whom it may concern:

Be it known that I, ULYSSE PERRIER, a citizen of the Republic of Switzerland, residing at New York, (Brooklyn,) county of Kings, State of New York, have invented certain new and useful Improvements in Coin-Controlled Apparatus, of which the following is a full, clear, and exact description.

My invention relates to coin-controlled apparatus; and it consists in the novel construction and arrangement of the operating parts hereinafter described.

The main object of my invention is to secure a simple, effective, compact, and durable mechanism whereby at the proper time and by the use of a suitable coin the apparatus may be operated by the movement of a suitable operating part.

The invention is applicable to coin-controlled machines irrespective of the purpose for which they are employed. Some of these machines are used for vending articles of merchandise, others for automatic-playing instruments, others for picture-machines, and others for a further variety of purposes too numerous to refer to in full.

In coin-controlled mechanism it is essential that the machine should be capable of detecting and rejecting as far as possible fraudulent pieces or dummies employed in an attempt to work the machine. These dummies are sometimes in the form of washers, pasteboard disks, leaden slugs, thin metal pieces, and irregular-outlined pieces, of a size capable of being inserted into the receiving-slot. By the present apparatus attempts to operate the vending-machine by the use of such pieces will be unsuccessful.

In the accompanying drawings, Figure 1 is a longitudinal sectional view of that portion of a vending-machine carrying my invention. Fig. 2 is a similar view, the parts being in a different position. Fig. 3 is a side elevation, the parts being in still another position. Fig. 4 is a plan view of the parts as they appear in the position as shown in Fig. 2, the top of the casing and the coin-chute being removed. Fig. 5 is an end view of Fig. 1, the coin being shown in dotted outline. Fig. 6 is a side elevation of the operating part.

In Fig. 1 of the drawings the parts are ar-

ranged in the position in which they are normally and with a coin of suitable denomination in place. In Fig. 2 the operating part is shown as advanced to where it has engaged 55 and advanced the coin and is about to eject the latter, and Fig. 3 shows the position of the parts at the extreme inward excursion of the operating part.

A is a portion of a casing or framework suitable to inclose the controlling mechanism.

B is a coin-chute preferably having internal dimensions approximately the size of the diametrical cross-section of a coin of the proper denomination, more importance being 65 attached to the narrower dimensions for the purpose of preventing a coin or dummy of greater thickness than the proper coin being inserted. By this provision the locking apparatus is only required to reject coins or dummies of less than the necessary thickness. 70

C is an operating part which in the drawings is shown in the form of a slide. A portion of the operating part projects outside of the casing A, so that it may be engaged by 75 the hand of the operator.

D is the base portion of the frame, upon which the slide portion C' of the operating part is supported. To prevent the vertical displacement of the operating part, various 80 means may be provided—for example, the edges of the slide C' may project underneath overhanging edges D' D' of the base D.

C' is a shovelled nose inclined toward the inner end of the operating part. 85

C' is a pin toward the inner end of the operating part.

C' is a second incline which may be formed upon the end of projection C' of the operating part. This projection C' is shaved off on 90 one side to pass pin F', hereinafter described. The rear portion of the projection C' may also be inclined, if desired, as at C'. The pin C' may be longitudinally adjustable—for example, by means of a set-screw C' or otherwise. 95 I preferably provide a spring E, by means of which the operating part C may be retracted, as shown in Fig. 1, although, if desired, the retraction may be accomplished manually.

F is a second slide supporting the frame by 100 which the merchandise is ejected when the machine is employed as a vending apparatus.

For illustrative purposes the merchandise-ejector is shown with a forward projection F', which may be successively thrust under or against the lowermost of a stack of articles to be vended—for example, chewing-gum—the arrangement of which articles is too well known to require detailed description. It is sufficient to say that each package may be supported one upon another and induced by gravity to move downward when the lowermost one is pushed away—for example, by a projection, such as F'. The slide F of the merchandise-ejector may have its lower edges extended under the aforesaid overhanging edges D' D' of the base to give certainty of alinement and prevent displacement. In the drawings the slide F is shown as resting upon the top of the slide C'. At the opposite sides of the slide F are extensions F² F⁸, and one of these extensions may pivotally support, as at f, a gate F³, which in turn carries a downwardly-projecting bearing-pin F⁴. Between the projections F² and F³ it is preferred to form a circular depression corresponding approximately to the shape of the proper coin. Upon the surface of this circular depression are located bearing devices F⁵ F⁵. Upon the rear of the gate F³ is formed an inclined plane or surface F⁶, which may, if desired, correspond approximately to the direction of the incline C⁴.

G G are springs of any suitable kind, so mounted as to bear with the desired pressure against the slide F, for example, as shown in Fig. 1, wherein it will be seen that a nose G' is projected into a depression F⁷, which depression may be provided to secure a firmer hold or bearing for springs G. In the specific form shown the springs G are mounted upon a lug G³ of the frame, while the noses G' G' may pass freely through suitable openings in additional supporting-lugs G⁴ of said frame. It will thus be seen that as long as the springs bear in said depressions F⁷ they will prevent the independent operation of the gate-carrying slide F, but will not interfere with the free movement of the operating part C and its slide C'. The inward and outward movement of the slide C' will cause the raised projection C⁵ to pass under the gate F³, which latter will be freely raised and lowered thereby. When it is desired to couple the slides F and C', a coin of a suitable denomination is inserted into a chute B, which directs it substantially into the position indicated in Fig. 1, although if said coin inclines rearwardly and rests upon the pin C³ it matters not. The pins F⁵ F⁵ stand in front of the coin until said coin is ejected. When a coin is in place, as indicated, the forward movement of the operating part C will cause the pin C³ to bear centrally against the near side of the coin, while the pins F⁴ and F⁵ F⁵ will bear against the opposite side of the coin near its periphery, said pins F⁴ and F⁵ F⁵ being such a distance apart as to prevent the tilting of

said coin. If the coin is of proper denomination, the adjustment of the pin C³ is such that the inclined face C⁴ of the operating part will have only just contacted with the inclined face F⁶ of the gate F³. Hence a further forward movement of the operating part will by the presence of the coin held as above stated advance the merchandise-ejector F'. By the presence of the coin, therefore, the two slides C' and F are so coupled together that they will advance simultaneously to a point where the merchandise shall have been ejected, at or about which instant the coin is ejected in the following manner: D⁴ is a raised projection having an inclined surface D². After the lower edge of the coin has engaged the incline of the projection D⁴ and the former is still further advanced it will ride up the incline D² and by the same be moved upwardly in the circular depression between the arms F² F⁸ until its lower edge becomes freed from the pins F⁵ F⁵, at which instant by further advance movement of the part C the coin is pushed over the inner edge of the inclined projection D⁴, from whence it may drop by gravity into a suitable receptacle not necessary to show. The apparatus having thus performed its duty, the parts may be retracted. Since that portion of the operating part C that is above the slide C' projects through a slot in the slide F, the said portion of the operating part will engage the shoulder at the rear end of said slot and will restore the slide F to its normal position. (Shown in Fig. 1.)

It will be seen that in the event an attempt is made to work the machine by means of a fraudulent piece—for example, a washer placed as the coin is placed in Fig. 1—the advance of the operating part will not be checked, as it is by a coin of the proper denomination, since the pin C³ will pass through the opening in the washer, whereupon the incline C⁴ will bear against the incline F⁶ and will raise the gate F³ until the pin F⁴ is above the washer, which latter will then be disengaged and upon further advance of the operating part will be pushed ahead and ejected into the coin-receptacle, the gate-carrying slide and merchandise-ejector in the meantime remaining still, since the washer is not a proper device to act as a coupling medium between slides C' and F.

In the event a lead slug of approximately the size of a suitable coin is employed the sharp points of one or more of the bearing-pins will cut into the soft metal of the slug before the vending-slide is advanced, the latter being held back by the engagement of the springs G or their equivalent. This cutting into the slug permits the operating part to advance to a point where incline C⁴ will raise the gate F³ in the manner previously described, whereupon the leaden slug will be ejected in the same manner as the washer, since the bearing-point F⁴ will be removed. The same result will follow an attempted fraudulent

operation of the machine by means of a disk of any soft material—for example, a paper disk.

If an attempt is made to operate the machine by means of a dummy of an outline not circular, such a dummy will not properly engage with the bearing-pins F⁴ F⁵ F⁶, which are preferably arranged so as to project only slightly into a perfectly-formed arc, and hence no proper bearing will be secured upon the far side of the coin. Therefore the advance of the operating part will deflect or tilt the fraudulent piece and eject it without advancing the gate-carrying devices and the merchandise-ejector.

From the foregoing it will be obvious that if an attempt is made to operate the machine with a piece of less than the proper thickness the incline C⁴ will rub against the incline F⁶ sufficiently to raise the gate F³, and thus remove the bearing F⁴, which when removed permits the thin slug to meet the fate of the leaden disk.

As to pieces of greater thickness than the coin of the proper size, no attention need be paid, since the opening in the chute B is not sufficiently large to permit the same being passed into the machine.

For convenience of expression I may call those portions of the device which carry the gate F³ the "gate-carrier." I may also refer to the bearing-pins or their equivalents as the "bearing-points" or "bearing devices."

As a variety of changes may be made from the specific apparatus shown and described, I desire to have it understood that the following claims are intended to cover and include all such alterations and changes as may be fairly considered to be within the spirit and scope of this invention.

What I claim is—

1. In a coin-controlled apparatus, a movable operating part, a carrier, a gate on said carrier, a plurality of bearing-points on said carrier and gate, a bearing-point on said operating part and means to operate said gate.

2. In a coin-controlled apparatus, a movable operating part, a carrier, a gate on said carrier, a plurality of bearing-points on said carrier and gate, a bearing-point on said operating part and means carried by said operating part to operate said gate.

3. In a coin-controlled apparatus, a movable operating part, an incline thereon, a carrier, a gate on said carrier, an incline on said gate to be engaged by said first-mentioned incline, a plurality of bearing-points on said carrier and gate, and a bearing-point on said operating part.

4. In a coin-controlled apparatus, a mov-

able operating part, a carrier, a gate on said carrier, a plurality of bearing-points on said carrier and gate, and a bearing-point on said operating part intermediate of the bearing-points on the gate-carrier and gate.

65

5. In a coin-controlled apparatus, a movable operating part, a carrier, a gate thereon, means carried by the operating part to move said gate, bearing-points to engage a coin and means to dislodge said coin from engagement with said bearing-points after the carrier has been advanced.

6. In a coin-controlled apparatus, a movable operating part, a carrier, a gate thereon, means carried by the operating part to move said gate, bearing-points to engage opposite sides of the coin, and an incline in the path of said coin to dislodge said coin from engagement with a bearing-point on one side thereof after the carrier has been advanced.

75

7. In a coin-controlled apparatus, a movable operating part, a carrier, means to hold said gate-carrier in a normally-retracted position, a gate on said carrier, bearing-points on said gate and carrier and operating part to engage a coin of the proper denomination and cause the advance of said carrier.

8. In a coin-controlled apparatus, a movable operating part, a slide therefor, a second slide, bearing devices carried by said second slide to engage one side of a coin, means carried by the operating part to engage the other side of a coin, and means whereby the position of one or more of said bearing devices shall be moved out of engagement with a piece other than a coin of suitable denomination.

9. In a coin-controlled apparatus, a movable operating part, a carrier, means for detachably engaging said gate-carrier in its retracted position, a gate on said carrier, bearing-points carried by said carrier, a pin carried by said gate, a bearing-pin carried by said operating part and means whereby the gate may be moved by the operating part.

100

10. In a coin-controlled apparatus, a movable operating part, a carrier, a gate carried thereby, bearing-points on said carrier and gate, means for detachably holding said carrier in the retracted position, a bearing-point carried by said operating part, and means to eject a coin by freeing it from engagement with one or more of said bearing-points after the carrier has been advanced.

Signed at New York, N. Y., this 27th day 115 of September, 1899.
